No. 15,487

Carpets

DESIGN.

H. HUNT.

CARPET.

No. 15,487.

Patented Oct. 28, 1884.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 15,487, dated October 28, 1884.

Application filed August 6, 1884. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures, herein specifically shown and claimed.

The accompanying photograph is a face view of a carpet showing my new design.

15 The design consists of four large groups, which, with their projecting sprigs, loosely fill in the intervening ground.

The group A is shown in the center of the photograph. It is a leaf and flower mass, with 20 many and varied leaf and blossom sprays projecting in all directions, as shown, and two prominent figures—a square figure on the right below and a scalloped circular figure on the left below. This group does not include the 25 large fan-like figure to the right of the center of the photograph nor the checkered ornament just above it to the left, both of which form part of the group C; but the group A does include the wavy ornament to the left of 30 the fan-like figure, and the blossom-spray extending outward and on the left of the checkered ornament.

The group B is shown at the upper and lower parts of the photograph. It is an open group 35 of flowers and leaves and blossom and lichen sprays. Below on the left is a prominent right-lined figure of irregular shape, having a lichen spray below it on its right and a single flower on its left, where it approaches the group D. 40 The patch of mottled ground, which appears to underlie this single flower, and also a part of the group D, does not belong to either group. A leaf of this group B on the left above appears to conceal a part of a spray of lichen belonging to the group C, and a leaf on the right appears to conceal, similarly, a part of a spray belonging to the group D; but there is no interblending of the groups in either case, and there can be no confusion as to the limits of 45 either.

The group C is shown at the right of the photograph above and at the left below the center. It has a small leaf-and-flower mass above, with surrounding checkered and other small ornamentation and short projecting flower-figures. Below on the left is a large fan-like figure, with a checkered ornament above it and a lichen-spray below. Below the group is a mural ornament terminating in a small flower-figure, and to the right of that is a large 55 scalloped figure, above which is a blossom and lichen cluster, the latter approaching the group B.

The group D is shown at the right of the photograph below and at the left above the center. There is a large circular figure to the left, and a flower mass above it and a leaf mass to the right. Above the group terminates in a leaf and a blossom-spray. On the right a leaf-spray approaches the group B, 70 and a lichen-spray approaches the group A. Below on the right is a spray of skeleton leaves, and on the left a cluster of blossoms and lichen-sprays approaching the group B. On the left above a leaf of this group approaches to the 75 large square figure of the group A, but does not interblend with it.

I claim—

1. The design for a carpet, consisting of the group A, substantially as shown and described.

2. The design for a carpet, consisting of the group B, substantially as shown and described.

3. The design for a carpet, consisting of the group C, substantially as shown and described.

4. The design for a carpet, consisting of the group D, substantially as shown and described.

5. The design for a carpet, consisting of the groups A, B, C, and D, substantially as shown and described.

90

HENRY HUNT.
